LINE INDICATING COPY HOLDER

Arthur L. Slee, San Francisco, Calif.

Application November 23, 1936, Serial No. 112,400

4 Claims. (Cl. 120—34)

My invention relates to improvements in line-indicating copy holders wherein a pair of superimposed sheets, slidably connected for limited relative movement, operates in conjunction with a line indicator movably superimposed upon said sheets and provided with improved means for engaging said sheets to permit movement in one direction only, relatively to said sheets, whereby said indicator may be moved intermittently over said sheets and copy thereon, when said sheets are intermittently reciprocated, one upon the other.

The primary object of the present invention is to provide a new and improved line-indicating copy holder.

Another object is to provide a new and improved device of the character described which may be easily and economically constructed either from sheets of card or pasteboard, to provide an extremely cheap but practical device, or from thin sheets of metal or other suitable material or composition or metal, to provide a device having great utility, maximum efficiency and extreme ease of operation.

A further object is to provide a new and improved line-indicating copy holder having many of the advantages and utilities of the more expensive devices now in use, but which may be produced at a greatly reduced cost and having a greater ease of operation.

A still further object is to provide a new and improved line-indicating copy holder that will be less bulky and much lighter in weight, and one which may be readily folded flat, so that the same may be easily placed within a drawer or easily carried in a brief-case or the like or otherwise transported from one position or place to another, to promote a greater range of utility and a more universal use of copy holders.

A still further object is to provide a more economically produced and efficiently operated and improved construction than the construction set forth in my copending application, Serial Number 89,102; filed July 6, 1936; for line-indicating copy holders, now matured into Patent No. 2,089,507, dated Aug. 10, 1937.

A still further object is to provide a new, improved, and greatly simplified construction whereby all of the metallic parts disclosed in said copending application and the cost of producing and assembling the same may be eliminated, and wherein a more durable, useful and efficient copy holder may be produced from four pieces of cardboard and a rubber band at a great-

ly reduced cost without sacrificing any of the utility or advantages of said copy holder.

I accomplish these and other objects by means of the improved device disclosed in the drawings forming a part of the present application, and in which—

Fig. 1 is a partly broken front elevation of my improved device;

Fig. 2 is a partly broken side elevation thereof;

Fig. 3 is a sectional view taken on line 3—3 of Fig. 1 in the direction indicated;

Fig. 4 is a broken plan view of the sheet engaging means; removed from said sheets;

Fig. 5 is a similar view with said means engaging the sheets, and taken on line 5—5 of Fig. 1 in the direction indicated;

Fig. 6 is a sectional view taken on line 6—6 of Fig. 1, in the direction indicated, disclosing another view of the manner in which said engaging means engages the sheets and operates;

Fig. 7 is a broken rear elevation of one end of the line indicator;

Fig. 8 is a sectional view of the interlocking spacer member, taken on line 8—8 of Fig. 1, in the direction indicated; and

Fig. 9 is a broken elevation disclosing the manner in which the sheet connecting tabs are formed.

Referring to the drawings:

The numeral 1 is used to designate what I term, for convenience, a base sheet, suitably cut, scored and folded to form a foot 2 and supports 3 and 4 interlocked to form a support for maintaining said sheet 1 in a substantially erect or inclined position, to facilitate the reading of copy supported thereby. The support 4 is cut from the approximate center of said sheet 1, leaving an opening 6, the purpose of which will hereinafter be more fully set forth.

The base sheet 1 is also provided with upper and lower vertically disposed vertical slits with lateral extensions to form struck up tabs 7, one of the lower tabs 7 having its upper end extending above its parallel adjacent tab a distance equal to a double line space of a standard typewriter. The base sheet 1 is also provided with oppositely disposed upper and lower notches 8 on opposite side edges thereof which normally register with similar notches 9 in opposite edges of what I term a copy sheet 11, slightly wider than the base sheet 1 and slidably mounted for limited vertical movement on said base sheet 1 by means of tabs 12, also struck up, which register with and slidably engage the adjacent edges of the slits forming the tabs 7 of the sheet 1. The tabs 12 are short-

er than the tabs 7 an amount equal to the double line spacing of a standard typewriter so that said copy sheet 11 is superimposed and slidably connected by said tabs 12 for limited movement upon said base sheet 1 to that extent.

When the tabs 12 are bent backwardly at right angles to the back of the copy sheet and inserted through the slits formed by the tabs 7 on the sheet 1 and then released, the natural resiliency 10 of the sheet material moves said tabs 12 to embrace the parallel adjacent edges of the slits of the tabs 7 while the same resiliency of said tabs 7 causes them to lightly press and hold said tabs 12 into slidable engaging relation with said edges 15 or opposite sides of the bar or portion 12' between said tabs 7, as fully disclosed in Fig. 3 of the drawings, thereby providing an effective sliding as well as a locking connection between the sheets 1 and 11, without other means than their own integrally formed tabs.

The tabs 12 are formed preferably by a cut midway and vertical between the folds or hinges thereof, indicated in dotted lines in Fig. 9 of the drawings. The cut forming the upper ends of 25 the lower tabs 12 is inclined to provide an inclined edge 14, one end of which is higher than the other end thereof by two standard typewriter line spaces, as disclosed in Figs. 1 and 9 of the drawings.

30 The copy sheet 11 is also provided with a central and backwardly bent tab 16 extending through the opening 6 of the base sheet 1 provided by cutting the easel support 4 therefrom. An ordinary rubber band 17 extends from the top of said support to said tab 16 and the tension of said rubber band 17 operates to normally retain the copy sheet 11 in its uppermost position on the base sheet 1 with its side notches registering with the side notches of said base sheet.

40 A suitable shelf or ledge 18 is formed upon the lower end of the copy sheet 11 to vertically support copy 19 and also to serve as a bar for operating the device. Slits are also provided in the upper end of said copy sheet 11 to produce tabs 21 for holding the upper edges of copy 19 and for aligning the same laterally with respect to said copy sheet 11.

45 A spacer 20 for regulating and limiting vertical movement of the copy sheet 11 to either single or double spacing comprises a bar 22 slidably mounted within a trough 23 formed at the lower edge of the base sheet 1. The spacer 20 has a tongue or struck up tab 24 which slidably engages a horizontal slot 26 in the lower end of the base sheet 1 and also has an extension 27 provided with a double fold upon itself to produce a fork 28 for straddling or embracing the inclined edge 14 of the copy sheet 11 and also containing a stop 29 with an inclined end 30 arranged parallel to and a single standard typewriter space away from said inclined edge 14 while the opposite or bottom edge 31 of said double fold engages the opposite edge 35 of the aperture formed by bending back the lower tabs 60 12 and inserting the same through the slits of the adjacent tabs 7, as disclosed in Figs. 1 and 2 of the drawings. The tab 24 sliding within its slot 26 adjusts and limits the amount of movement of the spacer 20 from single to double spacing, in 65 a manner hereinafter more fully set forth.

70 An indicator 34 comprises a single sheet superimposed upon the copy sheet 11 and provided with depending guides 36 at opposite ends thereof for slidably engaging opposite side edges of 75 the superimposed sheets 1 and 11 to normally re-

tain said indicator 34 in transverse or horizontal alignment with copy lines on the copy 19.

The indicator 34 is also provided with rearwardly extending portions 38 held in such position by braces 39 formed integrally with said indicator directly back of and attached to the guides 36. The portions 38 are arranged at opposite ends of the indicator 34 and each is provided with a slit 41 arranged substantially parallel to the planes of the sheets 1 and 11 and 10 providing integrally formed tabs 42 and 43 for embracing the front and rear or remote surfaces of said sheets, as disclosed in Figs. 2, 5, and 6 of the drawings. The rear tab 42 is shorter than the front tab or detent 43 so that said rear tab 15 may be readily inserted into proper engaging relation with said sheets by the front tab operating as a stop, said front tab 43 being longer than the depth of said notches 8 and 9.

These integrally formed tabs 42 and 43 operate the indicator 34 by engaging remote or opposite surfaces of the sheets 1 and 11 in the same manner as described, illustrated and claimed for the detents of my copending application above referred to. Thus these tabs are in effect and 20 operate pawls, detents or engaging tabs integrally formed with the indicator itself, to prevent movement of the indicator 34 in one direction and to move said indicator with a moved sheet, thereby effecting a saving of cost and labor in 25 producing separate detents or tabs as well as the cost and labor of properly positioning and assembling the same on said indicator. Actual experience has demonstrated that these tabs are a further improvement over the pointed metal detents 30 as they do not scratch or mar the surfaces of the sheets, when formed of cardboard, but frictionally and very effectively engage said sheets when reciprocated one on the other, for moving said indicator with said moved sheet.

40 Each slit 41 is preferably provided with a transverse extension or slit 44 which serves two purposes. Firstly, it provides a slightly greater resiliency for the front tab 43, thereby permitting it to more readily engage and release its sheet 11 when the same is reciprocated, and, secondly, it engages the side edges of the slightly wider copy sheet 11 without engaging the edges of the base sheet 1 and thereby assists the front tab in the performance of its function and also 45 limits movement of the indicator 34 laterally upon the copy sheet 11 and thereby acts as a guide above and in conjunction with the guides 36, for constantly retaining horizontal alignment of said indicator as it traverses lines of copy on the copy 50 sheet 11.

The upper edge of the indicator 34 is provided with a beveled edge 46 having a standard typewriter scale 47 thereon, said beveled edge 46 being formed integrally with said indicator 34 by 55 scoring and bending the said edge backwardly beyond the plane of said indicator 34. This provides a direct guide lying close to the surface of the copy so that the line being copied may be rendered more conspicuous by its proximity to 60 the upper edge of said indicator instead of in spaced relation to the back thereof.

In operation:

Copy 19 is placed with its lower edge resting upon the shelf or ledge 18 of the copy sheet 11 70 and effectively held in position by the indicator 34 or, the upper corners of said copy 19 may be inserted under the tabs 21 to align said copy 19 laterally with the copy sheet 11 and with the typewriter scale 47.

The indicator 34 is placed at the upper end of said copy sheet 11 and copy 19 thereon and the shorter tabs 42 are then inserted through the oppositely positioned upper registering notches 8 and 9, the longer tabs 43 operating as stops to properly position said indicator with respect to the superimposed sheets 1 and 11. The indicator is then moved downwardly until the tabs 42 and 43 embrace the back and front surfaces of the

10 said sheets 1 and 11 respectively, directly below said registering notches, as disclosed in Figs. 5 and 6 of the drawings, and the upper edge of the bevel 46 rests below the first line to be copied.

After the first line is copied the indicator 34 and bevel 46 thereof are moved below the next line to be copied by pressing downwardly upon the shelf 18 which moves the copy sheet 11, against the tension of the rubber band 17, downwardly until the inclined edge 14 on said sheet 11 contacts the inclined end 30 of the stop 29. As said indicator moves downwardly the front tabs 43, operating as pawls or detents, embrace and bind against the front surface of the copy sheet 11 and said indicator 34 is moved downwardly an equal distance with said sheet 11, the rear tabs 42 substantially releasing their frictional engagement with the rear surface of the base sheet 1 as said indicator is lowered. When the copy sheet 11 is released it is instantly returned to its original or upper position by the tension of the rubber band 17 and during such return movement the rear tabs 42 frictionally engage and bind against the rear surface of the base sheet 1 to prevent a return movement of the said indicator while the front tabs or detents 43 substantially release their engaging relation with the front surface of the copy sheet to permit the same to be quickly and easily returned to its original or upper position. Repeated operation 40 of the above will intermittently move the indicator to the bottom of the copy sheet when the tabs 42 and 43 will register with the notches 8 and 9 and the engaging relation of said tabs with their respective sheets will be automatically released. The indicator 34 then may be easily removed from the device by moving the rear tabs 42 of said bar 34 forwardly through the lower registering notches 8 and 9 of the base sheet 1 and copy sheet 11, respectively.

50 After a page of copy has been copied it may be turned back over the top of the sheets 1 and 11, as disclosed in the upper right hand corner of Fig. 2 of the drawings, or said sheets, if loose, may be removed from the holder. The indicator 55 is then repositioned as above described and the operation above described, may be repeated.

When the spacer 20 is positioned at its extreme left, as indicated in Fig. 1 of the drawings, the distance between the inclined edge 14 of the 60 copy sheet 11 and the inclined end 30 of the stop 29 is equal to a single typewriter line space. Therefore, when said copy sheet 11 has moved downwardly a distance equal to a single space it is stopped by contact of said inclined edge 14 with said inclined end 30. If the spacer 20 is moved to the opposite or extreme righthand position the

inclined end 30 will be two spaces removed from said inclined edge and therefore the sheet 11 may be moved a double space before the inclined edge 14 thereof encounters said inclined end 30.

It is obvious, from the foregoing, that I have provided a greatly simplified and improved structure having practical utility and efficiency and one which may be economically produced and easily operated, the amount of energy required to intermittently lower the indicator being slightly more or greater than that of the rubber band tension.

Having described my invention I claim—

1. A copy holder comprising a base sheet; a copy sheet slidably superimposed on said base sheet; and a line indicator mounted upon said sheets and having a slit in each end portion thereof for embracing said sheets, the opposite edges of said slits forming sheet engaging tabs for normally preventing movement of said indicator on said sheets and for engaging one of said sheets, when moved upon the other, for moving said indicator with said moved sheet.

2. A copy holder comprising a pair of superimposed sheets slidably connected; and a line indicator mounted on said sheets and having slits, the opposite edges of said slits embracing opposite sides of said sheets to normally hold said indicator against movement on said sheets and to engage one sheet, when moved upon the other, to move said indicator with said moved sheet.

3. A copy holder comprising a pair of superimposed sheets slidably connected for limited relative movement; and a line indicator slidably mounted upon said sheets and having slits therein for embracing opposite sides of said sheets for normally preventing movement of said indicator on said sheets and for engaging one sheet, when moved in one direction upon the other, for moving said indicator with said moved sheet and for substantially releasing said moved sheet and engaging said other sheet when said moved sheet is returned to original position, whereby said indicator may be moved intermittently over one 45 of said sheets when either sheet is reciprocated upon the other.

4. A copy holder comprising a pair of superimposed sheets slidably connected for limited relative movement; a line indicator slidably mounted upon said sheets and having integrally formed tabs for embracing opposite sides of said sheets for normally preventing movement of said indicator on said sheets and for engaging one sheet, when moved relatively to the other, for moving said indicator with said moved sheet and for substantially releasing said moved sheet and engaging said other sheet when said moved sheet is returned to original position, whereby said indicator may be moved intermittently over one 50 of said sheets when either sheet is reciprocated upon the other; and guiding means formed integrally with said indicator for slidably engaging opposite sides of said superimposed sheets to hold said indicator in substantially correct alignment with lines of copy on said holder.

ARTHUR L. SLEE.
